PROCESS FOR THE PREPARATION OF
EASILY WATERSOLUBLE ACID SULPHURIC
ACID ESTER DERIVATIVES OF INDAN-
THRONE DYESTUFFSRoger Ratti, Basel, Switzerland, assignor to
Durand & Huguenin S. A., Basel, SwitzerlandNo Drawing. Application November 5, 1931,
Serial No. 573,306. In Germany November 14,
1930

5 Claims. (Cl. 260—31)

The U. S. Patent No. 1,448,251 discloses a process for the manufacture of water soluble esterlike derivatives of vat dyestuffs, especially valuable for dyeing and printing purposes, consisting in treating the leuco compounds of vat dyestuffs with chlorosulphonic acid in presence of a tertiary base, and transforming the thus formed ester into a stable alkali salt. This process has been modified and improved since.

10 It is known, that the vat dyestuff N-dihydro-1,2,2',1'-dianthraquinone-azine (indanthrone), when transformed into its leuco compound and the latter esterified according to the process described in the aforesaid patent, yields a stable 15 and to a certain extent water soluble product. But as the product is intended to be applied for printing textile fibres, its water solubility is insufficient. The analysis shows, that the product in question is a disulphuric acid ester of leuco 20 N-dihydro-1,2,2',1'-dianthraquinone-azine.

Surprisingly it has now been found, that a new estersalt, also derived from the vat-dyestuff N-dihydro-1,2,2',1'-dianthraquinone-azine, but of much better solubility than the one manufactured 25 according to the said Patent No. 1,448,251 can be obtained by a new method of working. The manufacture of this new estersalt does not start from N-dihydro-1,2,2',1'-dianthraquinone-azine (ordinary indanthrone), but from 1,2,2',1'-dianthraquinone-azine obtained from the former by oxidation.

30 By simultaneous reduction and esterification of this 1,2,2',1'-dianthraquinone-azine in known manner with the aid of an addition product of a tertiary base and SO₃, in presence of an excess of the tertiary base, in presence of a metal and when carrying out the esterification in the absence of any moisture, so that during the operation no acid can be formed, a substance is obtained which 35 can be converted into a stable easily soluble alkali-salt. It appears that in this process the four keto-groups of the anthraquinones are simultaneously reduced to enolic-groups and esterified, so that the tetrasulphuric acid ester of tetrahydro-1,2,2',1'-dianthraquinone-azine is formed.

In a similar way a valuable poly-ester (probably a mixture of a tri- and tetra-sulphuric acid ester) is obtained, when treating a chloro-derivative of the 1,2,2',1'-dianthraquinone-azine in the above said manner.

The above mentioned poly-esters are exceedingly sensitive against acids. If an acid is added to a solution of such an ester, a violet or blue-

violet almost insoluble body is precipitated. It is identical or very similar to the well known diester. It is an unexpected fact that by acid oxidation (hydrolysis and oxidation) not the parent material, that is 1,2,2',1'-dianthraquinone-azine, but N-dihydro-1,2,2',1'-dianthraquinone-azine (indanthrone) is formed. Therefore, these ester salts can be used for dyeing and as they show a very good water solubility, they are particularly suitable for printing textile fibres.

10 The same or similar bodies appear to have already been obtained, but in quite a different manner, namely by means of oxidation of the 2'-aminoanthrahydroquinone-disulphuric acid ester or its chloro-derivatives in alkaline solution (see 15 German Patent No. 470,809 and British Patent No. 334,902).

The new process is illustrated by the following examples:

Example 1

20

20 grs. of pure SO₃ are added drop by drop, while cooling with ice and stirring, to 250 grs. of water free pyridine. To this addition-product is added in the cold, while stirring, a mixture of 25 22 grs. of 1,2,2',1'-dianthraquinone-azine and 22 grs. of copper powder. The mass is heated up to 70° C. in a dry current of nitrogen, free from air, and kept at this temperature for about 1½ hours. The color of the mass, which at 30 first is green, turns slowly to blue, afterwards to violet and finally to deep-red. The mass is allowed to cool down and then poured into a mixture of 70 grs. of caustic soda lye (30%) and ice. Then the solution is heated up for a short 35 time to 50° C., separated from copper by filtration and the pyridine distilled off under a vacuum. The thus obtained alkaline solution is of a yellowish brown color and shows a strong, green fluorescence. By evaporation in vacuo the 40 solution is concentrated to a paste.

Example 2

25 grs. of pure SO₃ are added drop by drop, while cooling with ice and stirring, to 250 grs. 45 of water free pyridine. To this addition-product is added in the cold, while stirring, a mixture of 25 grs. of dichloro-1,2,2',1'-dianthraquinone-azine (obtained according to the German Patent No. 229,166) and 25 grs. of copper 50 powder. The mass is heated up to 70° C. in a dry current of nitrogen, free from air and kept at this temperature for about 1½ hours. It is then allowed to cool down and poured into a solution of 35 grs. of potassium hydroxide in 55

litres of ice-water. The mass is heated up for a short time to 50 to 60° C., the red solution is separated from the copper by filtration and the pyridine is distilled off under a vacuum. The thus obtained alkaline solution is of a deep red color and shows a strong, green fluorescence. By evaporation in vacuo the solution is concentrated to 2 litres. On adding 200 grs. of potassium chloride, the red potassium salt of a relatively difficultly soluble ester (probably a tri-ester) is precipitated. This ester is separated off by filtration. The filtrate is of a brown color and shows a green fluorescence. By evaporation in vacuo an easily soluble product, probably a tetra-ester is obtained.

The product, suitable for printing purposes, being a mixture of the sodium salt of the two esters will be obtained, when pouring the red colored mass into a mixture of 70 grs. of caustic soda lye (30%) and 3 litres of ice-water instead of pouring it into a solution of potassium hydroxide, as indicated above. The mass is left standing for a few hours and heated up afterwards, while stirring, to 50-60° C. After separation from copper by filtration, the solution is concentrated by evaporation in vacuo to a paste.

By the same working operation a mixture of poly-esters results, when for example a trichloro-derivative of the 1,2,2',1'-dianthraquinone-azine is used as starting material.

The process of esterification as illustrated by the above examples is not limited to the use of pyridine and copper. Another tertiary base and another metal, known to be suitable in vat-dye-stuff esterification and for reducing purposes, respectively, may be used.

What I claim is:—

1. A process for the preparation of easily watersoluble acid sulphuric acid esters of the leuco compound of a 1,2,2',1'-dianthraquinone-azine, with the aid of an addition product of a tertiary base, suitable for esterification, and SO_3 , in presence of an excess of the tertiary base and a metal as used for reduction, said process yielding easily soluble tri- and tetra-esters and consisting in using an 1,2,2',1'-dianthraquinone-azine as starting material and carrying out the esterification in the absence of any moisture, so that no acid can be formed during the operation.
- 50 2. A process for the preparation of easily watersoluble acid sulphuric acid esters of the

5 azine, with the aid of an addition product of a tertiary base, suitable for esterification, and SO_3 , in presence of an excess of the tertiary base and a metal as used for reduction, said process yielding easily soluble tri- and tetra-esters and consisting in using a halogenated 1,2,2',1'-dianthraquinone-azine as starting material and carrying out the esterification in the absence of any moisture, so that no acid can be formed during the 10 operation.

3. A process for the preparation of easily watersoluble acid sulphuric acid esters of the leuco compound of a 1,2,2',1'-dianthraquinone-azine, with the aid of an addition product of a 15 tertiary base, suitable for esterification, and SO_3 , in presence of an excess of the tertiary base and a metal as used for reduction, said process yielding easily soluble tri- and tetra-esters and consisting in using chlorinated 1,2,2',1'-dianthraquinone-azine as starting material and carrying out the esterification in the absence of any moisture, so that no acid can be formed during the 20 operation.

4. A process for the preparation of easily 25 watersoluble acid sulphuric acid esters of the leuco compound of a 1,2,2',1'-dianthraquinone-azine, with the aid of an addition product of a tertiary base, suitable for esterification, and SO_3 , in presence of an excess of the tertiary base and a metal as used for reduction, said process yielding easily soluble tri- and tetra-esters and consisting in using a dichloro-1,2,2',1'-dianthraquinone-azine, as starting material and carrying out the esterification in the absence of any moisture, so that no acid can be formed during the 30 operation.

5. A process for the preparation of easily 35 watersoluble acid sulphuric acid esters of the leuco compound of a 1,2,2',1'-dianthraquinone- 40 azine, with the aid of an addition product of a tertiary base, suitable for esterification, and SO_3 , in presence of an excess of the tertiary base and a metal as used for reduction, said process yielding easily soluble tri- and tetra- 45 esters and consisting in using 1,2,2',1'-dianthraquinone-azine as starting material and carrying out the esterification in the absence of any moisture, so that no acid can be formed during the 50 operation.

ROGER RATTI.
